Patented Aug. 12, 1913.

UNITED STATES PATENT OFFICE.

ALEXANDER BURKHARDT, OF INDIANAPOLIS, INDIANA.

MULTISPEED-TRANSMISSION GEARING.

1,070,228.

Specification of Letters Patent.

Patented Aug. 12, 1913.

Application filed November 22, 1912. Serial No. 732,975.

To all whom it may concern:

Be it known that I, ALEXANDER BURKHARDT, a citizen of the United States, residing at Indianapolis, in the county of Marion and State of Indiana, have invented a new and useful Multispeed-Transmission Gearing, of which the following is a specification, reference being had to the accompanying drawings and to the letters and figures 10 of reference marked thereon.

This invention relates to a train of gearing and supports therefor that may be used in various situations for transmission of power, the invention having reference more 15 particularly to gearing whereby power may be transmitted at various speeds.

The object of the invention is to provide improved gearing that shall be so constructed as to be adapted to be employed 20 either for increasing or decreasing speed and which may be so constructed as to be simple and powerful.

A further object is to provide improved gearing that may be employed either for 25 converting rotary motion into reciprocatory motion or reciprocatory motion into rotary motion.

With the above mentioned and other objects in view, the invention consists in the 30 novel parts and in the arrangement thereof in gearing of the above mentioned character, and in the specific combinations of parts as hereinafter particularly described and further defined in the accompanying claims.

Referring to the drawings, Figure 1 is a side elevation of the improved gearing; Fig. 35 2, a front elevation thereof; Fig. 3, a vertical section on the line A A in Fig. 2, omitting portions of Fig. 1; Fig. 4, a front elevation of a retaining ring preferably employed; Fig. 5, a fragmentary rear elevation; Fig. 6, a front elevation of the frame 40 of the gearing; and Fig. 7, a fragmentary rear elevation of the main wheel partially 45 broken away.

Like reference characters throughout the drawings, indicate like elements or features of construction herein referred to.

The gearing is provided with a suitable 50 supporting frame which may be variously constructed so as to be adapted to be supported in various positions or with respect to various machinery, and for the purpose of illustration comprises a base 1 adapted

to be bolted securely in a suitable position, 55 as upon a floor, and in the present case supports a suitable frame 2 in upright position. The frame has a journal box 3 having a cap 4, another journal box 5 having a cap 6, and a box 7, the boxes being in one and 60 the same plane, the plane preferably being vertical as illustrated but obviously may be horizontal if preferred to so arrange the boxes. The frame comprises also a ring-like portion 8 extending concentrically 65 about the box 5 and having an external bearing portion 9 for rotatably supporting the main wheel and having also a flange 10 for guiding the wheel, said ring-like portion having bolt holes 11 therein. An annular 70 main wheel 12 of novel construction is provided which has a flange 13 on one side thereof that is bored out to form a suitable bearing portion 14 that is rotatably mounted on the bearing portion 9 and retained 75 thereon by means of a retaining ring 15 secured by means of bolts 16 inserted in bolt holes 17 formed in the ring, the ring being placed against the front of the ring-like portion 8, and in some case has recesses 18 and 80 19 to clear portions of the boxes 7 and 3 respectively. The flange 13 has an external crowning pulley face 20 adapted to drive a belt. The periphery of the wheel 12 has gear teeth 21 thereon in order to drive or be 85 driven by another gear wheel, and the periphery preferably has a flange 22 adjacent to the gear teeth, and a crowning pulley face 23 beyond the flange for driving a belt. The wheel is provided also with internal 90 gear teeth 24 whereby the wheel may drive or be driven by another wheel. The main wheel 12, as will be seen, is of annular form and on its front is provided with a suitable cross bar or plate 25 preferably having a 95 counter-weight 26, and preferably is detachably secured to the wheel, and has a slot 27 therein in which a crank pin 28 is adjustably secured so as to be placed at different distances from the axis of rotation of 100 the wheel, in order that the wheel may be driven by a pitman, or may operate a pitman of a pump, for instance, and thus convert rotary motion into reciprocatory motion.

A shaft 29 is rotatably mounted in the box 5 and a pinion 30 is secured fixedly to the forward end portion thereof and is

guided against the box, a collar 31 being secured to the shaft against the opposite end of the box. Preferably a shaft support 32 is provided and is adapted to be suitably supported and rotatably supports the rearward portion of the shaft 29 on which a pulley 33 preferably is secured for driving a belt if desired. A shaft 34 is rotatably supported in the box 3 and a pinion 35 is secured thereto in contact with the forward end of the box and in mesh with the pinion 30 and also with the gear teeth 24, a collar 36 being secured to the shaft at the opposite end of the box.

15 Preferably a suitable shaft support 37 is employed which rotatably supports the rearward portion of the shaft 34, a relatively small pulley 38 being preferably secured to the shaft for driving a belt if desired. A stub shaft 39 is supported in the bearing 7 and preferably fixed therein and it rotatably supports a pinion 40 at the forward end thereof, the pinion being in mesh with the pinion 30 and also with the gear teeth 24. It will be seen that whether the shaft 29 drives the main wheel 12, or the wheel drives the shaft, the strains are equalized on opposite sides of the shaft. It is obvious, however, that in small sizes of the gearing the transmission of motion may be effected between the shaft 29 and the main wheel 12 by either pinion 35 or 40.

In practical use, the initial motion may be given to the shaft 29 and transmitted through the main wheel 12 from two pulleys or one toothed gear wheel as rotary motion or by means of the crank pin 28 to impart reciprocating motion. Or, in some cases a reciprocating engine may impart motion by means of the crank pin 28 to the main wheel 12 and thence to the shafts 29 and 34 which may drive or transmit the motion by means of wheels thereon, and motion may be transmitted to machinery also by the main wheel 12 as will be obvious.

Having thus described the invention, what is claimed as new is:—

1. Gearing including a rotatable annular main wheel having a crank-pin and also internal gear teeth and external gear teeth, a rotatable shaft, and gearing connecting the shaft with the internal gear teeth of the main wheel.

55 2. Gearing including a rotatable annular main wheel provided with a crank-pin and having internal gear teeth and also external gear teeth, the wheel having also two pulley portions of different diameter on its periphery.

60 3. Gearing including a rotatable annular main wheel having internal gear teeth and also two external pulley faces differing in diameter, a rotatable shaft, and gearing connecting the shaft with the internal gear teeth of the main wheel.

4. Gearing including a frame having an annular bearing, an annular main wheel having a flange rotatably mounted on the bearing, the wheel having also internal gear teeth, a shaft rotatably mounted in the frame, and a pinion fixed to the shaft in mesh with the internal gear teeth.

5. Gearing including a frame having an annular bearing, an annular main wheel having a flange rotatably mounted on the bearing, the flange having an external pulley face, the wheel having internal gear teeth, and a pinion rotatably supported by the frame in mesh with the internal gear teeth.

80 6. Gearing including a frame having two journal boxes and also an annular bearing extending about the two boxes, an annular main wheel rotatably mounted on the annular bearing and having internal gear teeth, two shafts rotatably mounted in the two journal boxes, and two pinions secured respectively to the two shafts and meshing each with the other, one of the pinions being in mesh with the internal gear teeth.

90 7. Gearing including a frame having a journal box and also an annular bearing extending concentrically about the box, an annular main wheel rotatably mounted on the bearing and having internal gear teeth and also a crank-pin, a shaft rotatably mounted in the journal box, a pinion fixedly secured to the shaft, and a pinion rotatably supported by the frame in mesh with the internal gear teeth and the first mentioned pinion.

100 8. In transmission gearing, the combination with a frame having three boxes in one and the same plane, of an annular main wheel rotatably mounted on the frame and having internal gear teeth, a shaft rotatably mounted in the middle one of the boxes and having a pinion thereon, a shaft rotatably mounted in another one of the boxes and having a pinion thereon in mesh with the internal gear teeth and also with the first mentioned pinion, a stub shaft fixed in the remaining one of the boxes, and a pinion rotatable on the stub shaft in mesh with the internal gear teeth and also with the first mentioned pinion.

110 9. In transmission gearing, the combination of a frame having two journal boxes and a bearing box in one and the same plane, the frame having also an annular bearing extending about all the boxes, an annular main wheel having a flange rotatably mounted on the annular bearing and having also internal gear teeth, a stub shaft fixed in the bearing box, two shafts rotatably mounted in the two journal boxes respectively, two supports rotatably supporting portions of the two rotatable shafts respectively, two transmission wheels secured to the two rotatable shafts respec-

tively, a pinion rotatably mounted on the stub shaft in mesh with the internal gear teeth, and two pinions fixedly secured to the two rotatable shafts in mesh each with the
5 other, one of the two pinions being in mesh with the internal gear teeth and the other in mesh with the first mentioned pinion.

In testimony whereof, I affix my signature in presence of two witnesses.

ALEXANDER BURKHARDT.
